UNITED STATES PATENT OFFICE

2,040,170

METHOD OF PRODUCING ARTIST'S MATERIAL

William H. Eader, Denver, Colo., assignor of one-third to Fred W. Bonfils and one-third to Albert De Bernardi, Jr., both of Denver, Colo.

Application May 26, 1931, Serial No. 540,029

6 Claims. (Cl. 41—41)

My invention relates to material that is adapted for the use of artists to quickly provide (in sharply contrasted black and white) shading, background, etc., in drawings from which zinc 5 etchings or printing plates are to be made; simplifying the work of the artist in making any desired shaded design in a drawing, and simplifying the process of producing such design on a printing plate, with more positive results 10 and at less expense than by methods now commonly used. The shading, background or the like, which has been previously prepared, is preferably subdued and capable of being brought out by the artist in the desired parts of the drawing. 15 This invention also relates to the method of producing said material for the use of artists.

Important objects of the invention are: (1) More satisfactory results from placing the patterns, designs, shading, background, etc., upon 20 the drawing instead of upon the printing plates during the process of their manufacture. (2) To obtain the truest of contrasts, in black and white, with no stains between the dots or lines of the desired pattern. (3) To appreciably lessen the 25 work of the artist. (4) To obtain more positive results with greater speed and at less expense, in transferring said design from the artist's drawing to the printing plate, by facilitating the preparation of the plate. (5) To provide said 30 artist's material, adapted to the use of pencil, ink or crayon, on which drawings can be made, stored, and held indefinitely without fading or damaging.

Another object of the invention is to eliminate 35 the use of all chemicals that are harmful to the user of the material, and eliminate such in the production of the material.

Further objects reside in details of the finished 40 product and in novel steps employed in the method used for production of same, which will appear in the course of the following description.

In the drawing like reference characters des- 45 ignate similar parts in the several views.

Figure 1 is a face view of a sheet of paper em- 50 bodying features of the present invention.

Figures 2, 3 and 4 are exaggerated, broken, 55 sectional views taken on the line 2—2 of Figure 1, illustrating various steps in the method of producing my material.

Figures 5 and 6 illustrate the use of the finished product, which will be explained more fully hereinafter.

Referring more in detail to the drawing, the 55 reference character 7 designates a sheet of paper

carrying a chemically developable emulsion of silver halide 8. Ordinary sensitized, photographic paper may be employed. I prefer to use a semi-matte, matte or carbon, as they are best adapted to the use of pencil, ink or crayon. 5

The desired design is printed on this sensitized paper. It is to be clearly understood that any desired design may be used, including dots, as shown in the drawing, figures, scrolls, lines, stipple, drawing or photograph of scene, portrait, 10 sketch, wash-drawing, or design produced in line etching or in half-tone reproduction, etc. The printing is preferably done with a sticky, gummy or adhesive substance forming a protective covering. Ordinary printer's ink has been found 15 suitable, but preferably a quick-drying, dense and heavy printer's ink is employed.

Assuming that the plate from which the paper is printed carries a design of dots, as shown in Figure 1, then the dots will be reproduced as 20 shown in said figure. The ink providing the dots is illustrated at 9. The ink is then allowed to dry sufficiently, in order to provide protective films for the parts of the sensitized face that are covered by the dots. It is preferred not to allow 25 the ink to harden, but only dry to a limited extent.

The next step in the process is to remove the chemically developable material in spaces 30 10 between the dots. This is preferably done 35 by applying to exposed parts of the film, by immersion, painting, or otherwise, a solvent of silver chloride, silver bromide or silver iodide, such as a solution of sodium thiosulphate, or what is known in the art as "hypo." If immersed, thirty seconds in a fifty per cent (50%) solution of sodium thiosulphate is usually a sufficient length of time. Of course different strengths of solution and different grades of paper take different periods of time. The sheet then merely carries dots 11 of sensitive material, each dot 9 being protected by the dot of ink superimposed thereon, as exemplified by Figure 3.

The solvent is then washed off with water, as 45 by placing the sheet in a pan of clear water for from five (5) to fifteen (15) minutes (ten minutes being a fair average). The water must be free from sodium thiosulphate. Running water is desirable, especially in a stream or spray, or in a pan or tray containing running water, in 50 order that no trace of sodium thiosulphate may remain in the water.

The next step is to wash off the ink. This may be done by wiping the sheet with wet cotton. Of course any well-known ink solvent may be used, 55

as gasoline, benzine or benzole. The sheet is then dried. The result is a sheet having light-sensitive dots 11, as shown in Figure 4. The dots are substantially invisible, though they may be faintly seen at times.

The product of the foregoing process is now ready for the artist. The artist draws the desired sketch 12 on the paper produced by the above described process. The drawing may either 10 be in pencil or crayon (to be inked in later) or in chemical-proof ink. The artist then applies any suitable developer to that portion 13 of the sketch where he desires to bring out the design. Surplus developer may be removed by blotting 15 or otherwise. The dots 13 are in practice no larger than the remaining dots on the sheet, but have been exaggerated in the drawing to indicate that they are of darker color. There are a number of good, well-known developers on the 20 market, which may be used to bring out and make permanent the portion of the design that is desired.

The remaining dots 14 on the sheet 7 may now be removed with any suitable solvent, as described 25 hereinbefore, such as sodium thiosulphate, which also removes any developer stains which, in time, might appear between dots.

The developer, in the process of bringing out the dots to form the desired design, may be applied by brush, orangewood stick, or otherwise. 30 The sheet may be immersed in or brushed with the solvent in the last step, since the dots 13 have already been set by the developer. The surplus solvent is preferably removed, as with a 35 blotter.

After following the foregoing steps, the product will have the design 13 in the desired parts of the drawing and the space 15 around the drawing will be white. If the artist merely penciled 40 his sketch at first, he may ink it in after the paper is dry.

It is thought clear that any design may be employed. As an example, white dots in a black background may be used.

45 It is to be understood that changes may be made in the details of the method and product without departing from the spirit and scope of the invention.

What I claim and desire to secure by Letters 50 Patent is:

1. A process of producing a positive chemically developable surface for the use of artists, consisting in printing upon a layer of chemically developable silver emulsion, soluble in sodium thiosulphate, a pattern that will protect the layer against the action of sodium thiosulphate, then subjecting the layer to a solution of sodium thiosulphate to remove the unprotected silver emulsion and then removing the protective pattern to 55 produce a chemically developable design.

2. A process of producing a positive chemically

developable surface for the use of artists, consisting in printing upon a silver halide emulsion layer, a pattern that will protect the layer against the action of sodium thiosulphate, then subjecting the layer to a solution of sodium thiosulphate to 5 remove the unprotected silver halide, and then removing the protective pattern to produce a chemically developable design.

3. A process of producing a drawing or design for making printing plates, consisting in printing 10 upon a silver halide emulsion layer, a pattern that will protect the layer against the action of sodium thiosulphate, then subjecting the layer to a solution of sodium thiosulphate to remove the unprotected silver halide, and then removing the 15 protective pattern to produce a chemically developable design, then producing upon the design, a drawing or the like, then developing the portion of the surface, corresponding with said drawing or the like, and finally subjecting the design to 20 the action of a solvent capable of removing the part of the design other than the developed portion.

4. A process of producing a drawing or design for making printing plates, consisting in print- 25 ing upon a silver halide emulsion layer, a pattern that will protect the layer against the action of sodium thiosulphate, then subjecting the layer to a solution of sodium thiosulphate to remove the unprotected silver halide, and then removing the 30 protective pattern to produce a chemically developable design, then developing a portion of the design, and finally subjecting design to the action of a silver halide solvent.

5. A process of producing a drawing or design 35 for making printing plates, consisting in print- ing a pattern upon a sheet of material coated with a silver halide emulsion layer, with a substance impervious to sodium thiosulphate, exposing the 40 coated surface to the action of sodium thiosulphate, to thereby remove the exposed silver halide, removing the impervious substance from the 45 pattern, applying a pictorial representation to the patterned surface of the sheet, developing portions of the pattern within the pictorial representation and applying a silver halide solvent to the processed surface of the sheet.

6. A process of producing a drawing or design for making printing plates, consisting in print- 50 ing a pattern upon a sheet of material coated with a silver halide emulsion layer, with a substance impervious to sodium thiosulphate, exposing the 55 coated surface to the action of sodium thiosulphate, to thereby remove the exposed silver halide, removing the impervious substance from the pattern, applying a pictorial representation to the patterned surface of the sheet, developing portions of the pattern within the pictorial representation, and applying sodium thiosulphate 60 to the processed surface of the sheet.

WILLIAM H. EADER.
